FIG. 3

FIG. 1 is a side elevational view of the pulpwood gantry rake showing the rotary lifting boom extending over one end thereof, the side not shown being the same as the side shown;

FIG. 2 is an end elevational view thereof, the end not shown being a mirror image of the end shown when the rotary lifting boom extends over the opposite end thereof; and

FIG. 3 is a top plan view thereof.

I claim:

The ornamental design for a pulpwood gantry rake, as shown and described.
